UNITED STATES PATENT OFFICE.

REINHOLD G. MARQUARDT, OF MILWAUKEE, WISCONSIN.

MATTRESS-SPRING.

1,278,188.

Specification of Letters Patent. Patented Sept. 10, 1918.

Application filed August 11, 1916. Serial No. 114,312.

To all whom it may concern:

Be it known that I, REINHOLD G. MARQUARDT, a citizen of the United States, residing at the city of Milwaukee, county of Milwaukee, and State of Wisconsin, have invented new and useful Improvements in Mattress-Springs, of which the following is a specification.

My invention relates to improvements in mattress springs, and the same is explained by reference to the accompanying drawing, in which Figure 1 represents a plan view of a portion of a mattress spring, Fig. 2 represents a side view of a portion of a 10 longitudinal series of links in connection with a portion of transversely arranged spirally wound wires, and Fig. 3 represents a plan view of one link and a portion of two other longitudinally arranged links, in 15 connection with spirally wound wires by which the longitudinal series of links are connected together.

Like parts are identified by the same reference numerals throughout the several 20 views.

1 represents one of the links, several of which, when connected together form the longitudinal series of links, a plurality of which series are shown in Fig. 1. 2 is a 25 transversely arranged spirally wound wire, a plurality of said wires being connected with said longitudinal series of links at short intervals between the end members of the mattress frame. 3 represents one of the 30 end members of the mattress frame, and 4, 4 represents the side members of such frame. The respective ends of the several series of links 1 are connected to the end members 3 of the mattress frame by spiral 35 springs 5, the springs at one end of the mattress frame being shown in Fig. 1. It will be understood that the opposite end of said mattress frame (not shown) is preferably provided with a similar series of spiral 40 springs 5, the springs at one end of the mattress frame being shown in Fig. 1. It will be understood that the opposite end of said mattress frame (not shown) is preferably provided with a similar series of spiral 45 springs 5 for connecting the opposite ends of the series of links 1 with the opposite end member of the frame. The spiral springs 5 are each provided at one end with hooks 6, which are preferably inserted through 50 the apertures 7 of the frame member 3, and the opposite ends of said spiral springs

5 are provided with hooks 8, which are inserted through the ends of the next adjacent links 1, as shown in Fig. 1.

When several series of links 1 have thus 55 been connected with the end frame members 3, as shown in Fig. 1, said several series 1 are connected together by the transversely arranged spirally wound wires 2, said spirally wound wires 2 being interlocked with said longitudinally arranged series of links as shown in Fig. 3, and such wires are thus interlocked together by revolving said spirally wound wires 2 simultaneously as they are extended across the 60 mattress spring, whereby the coils of wire 9 are intertwined with the opposing ends of each pair of links, as most clearly shown in Fig. 3.

It will be understood, that as the spirally 65 coiled wire 2 is revolved, the end 10 of such wire is caused to pass between the wires 11, 11 of one link and the members 12, 12 of the next adjacent link as shown in said Fig. 3, when by continuing the revoluble 70 movement of said spirally wound wire, the end 10 thereof is caused in like manner to become intertwined with the next adjacent links of the several series throughout the mattress spring. Thus each spirally wound 75 wire between the respective ends of the mattress frame is in like manner connected with the several longitudinal series of links.

Attention is directed to the fact that each 80 link is oval in form, the opposite sides curving away from each other in the middle of the link and converging at both ends, whereby such links, when submitted to excessive pressure, are caused to straighten out and the respective sides are thereby caused to 85 approach each other and thus increase the length of the series, whereby the mattress is made much more elastic than it would otherwise be if the sides of such links were 90 made straight.

Having thus described my invention, what I claim as new, and desire to secure by Letters Patent, is—

In a device of the described class, the combination of a plurality of longitudinal 100 series of links, each link being formed of a single piece of resilient wire, a V-shaped

bend at one end, and a pair of hooks at its opposite end, the respective side members of each link being curved outwardly from its extreme ends toward its center, a plurality of transversely arranged coiled wires, each coiled wire being interwound with said outwardly curved links at their several points of contact, said links being adapted by their curved shape to expand and con-

tract as they are subjected to a greater or less pressure.

In testimony whereof I affix my signature in the presence of two witnesses.

REINHOLD G. MARQUARDT.

Witnesses:

JAS. B. ERWIN,
FREDERICK W. NOLTE.
